PAPER STRAP FORMING MACHINE

Frank A. Grant, Vancouver, British Columbia, Canada, assignor, by mesne assignments, to Paper Strap, Inc., Portland, Oreg., a corporation of Oregon

Application July 19, 1947, Serial No. 762,169

11 Claims. (Cl. 270—94)

1

The present invention relates to machines for making paper strap.

Relatively durable strap may be formed from a web of paper by folding over the opposite edge portions thereof a plurality of times upon itself and which strap is suitable for many uses. It is the general object of the present invention to provide a relatively simple, compact machine for producing such paper strap in quantity.

A further object of the present invention is to provide a machine of the class described which is capable of high speed operation.

Another object of the invention is to provide a machine of the class described having all working parts readily accessible for maintenance purposes.

Another object of the invention is to provide a paper strap folding machine having all parts so arranged that the web may be threaded therethrough with a minimum of difficulty.

And a further object is to provide a machine comprising relatively few parts of simple design and of low manufacturing cost.

For a consideration of what is believed novel and inventive, attention is directed to the following description taken in connection with the accompanying drawings while the features of novelty will be pointed out with greater particularity in the appended claims.

In the drawings, Fig. 1 is a vertical sectional view of a machine constructed in accordance with one form of the present invention and taken along the line 1—1 of Fig. 2; Fig. 2 is a plan view of the machine shown in Fig. 1 with the paper web omitted; Fig. 3 is an end view of the machine taken along line 3—3 of Fig. 2; Fig. 4 is a view taken along the line 4—4 of Fig. 1; Fig. 5 is a view taken along the line 5—5 of Fig. 1; Fig. 6 is an enlarged view of one detail incorporated in the machine; Fig. 7 is an enlarged fragmentary view illustrating further details of the machine; Fig. 8 is a view taken along line 8—8 of Fig. 2; and Fig. 9 is an enlarged, diagrammatic view illustrating the mode of operation of certain parts of the machine.

Referring now to the drawings, the machine of the invention is mounted upon a base plate 10 affixed to the top of the pedestal 11. A supply roll 12 of paper is adapted to be mounted upon a suitable supporting means 13 attached to the pedestal 11. The web 14 from the roll 12 after passing through the folding machine indicated generally by the reference character 15 and formed into a strap thereby is wound up on a take up roll indicated at 16. The web from the

2

roll 12 passes around the front end of the machine over a guide roller 20 from whence it passes under the roller 21 mounted between the ends of a pair of pivoted bracket arms 22. The bracket arms 22 are biased by a suitably arranged spring 19 in the counterclockwise direction as viewed in Fig. 1.

The machine 15 comprises a pair of opposite parallel side frame members 24 and 25 formed, in this instance, of steel plate and which are secured along their lower edge portions onto the base plate 10. For reasons as will subsequently appear, the upper portions of the frame members are semi-circular in shape while the plates are further provided with relatively large circular openings 26. The paper web 14 is formed into paper strap by coaction of a multiplicity of rollers and other elements mounted between the side frame members adjacent the peripheral portions thereof surrounding the openings 26. The folding mechanism operates in such a manner as to fold over the opposite outer edge portions of the web, one layer at a time, and upon the same side of the web until at the end of the successive folding stages the inwardly folded edge portions, each comprising a plurality of layers, substantially meet along the center line of the web but do not overlap each other. For facilitating the folding of the web, suitable scoring means are provided at the inlet to the machine while adjacent the discharge end further means are provided for setting the folds and also for imparting a degree of flexibility thereto.

The machine is driven by an electric motor 28 through a belt 29 extending around the driven pulley 30. The pulley 30 is mounted upon the end of a shaft 31 suitably journaled within the frame members 24 and 25. Secured to the shaft 31 is a rubber faced flanged pulley 33 around which the folded strap is trained and whereby the web is pulled through the machine. It is to be understood that, for starting the machine, the web must first be threaded through the successive stages of the machine and brought into engagement with the friction pulley 33.

While any suitable means may be provided for scoring the surface of the web 14, the scoring means in this instance comprises a pair of cooperating rollers 35 and 36. As illustrated in the enlarged fragmentary view of Fig. 7, the upper roller 35 is provided with a plurality of suitably spaced circumferential V-shaped ridges 37 while the lower roller 36 is provided with cooperating V-shaped grooves 38 aligned with the ridges 37. A plurality of web supporting, or fold setting

rollers 40, 41, 42 and 43 rotatably mounted between the frame members are arranged in a spaced apart relation and upon the same side of the path of travel of the web through the machine, and preferably on the inside of the generally circular path as viewed in Fig. 1. A plurality of other rollers 44, 45, 46 and 47, referred to for convenience hereinafter as folder rollers, are mounted between the side frame members and upon the opposite side of the path of travel of the paper web with respect to the rollers 40—43, inclusive. These folder rollers 45—47 are suitably mounted upon the ends of corresponding individual fixed brackets and which, in turn, may be adjusted so as to swing the roller carried thereby into operative engagement with the web. The folder roller 44 is mounted between the scoring roller 35 and the first set of supporting rolls 40. As illustrated more clearly in the view of Fig. 4, the folder roller 44 has a length corresponding substantially to the width of the spacing between the two outermost scores formed adjacent the opposite edges of the web 14. The opposite edge portions of the web thus overhang the opposite ends of the roller 44 and are free to curve upwardly adjacent the opposite ends of the roller 44, as illustrated in the view of Fig. 9.

Passing from the roller 44 the web then proceeds through the stationarily mounted deflector element 50 which is illustrated more clearly in the enlarged view of Fig. 6. The deflector element 50 is formed of a length of rod and which is provided with a slot 51 open along its upper side, the width of the slot 51 being slightly wider than the spacing between the two outermost scores formed in the paper web. Inwardly extending fingers 52 overhanging the opposite ends of the slot 51 engage with the outer edge portions 14a of the web and guide them inwardly of the web as shown in Fig. 6. As the web proceeds upwardly over the next adjacent set of supporting rollers 40, the edge portions 14a are pulled down flat against the upper surface of the intermediate portions of the web 14. In passing over the rollers 40, the path of travel of the web is changed through a considerable angle and, due to the differential in radius between the intermediate web portion and the folded edge portions, the increase in tension in the edge portions causes a certain amount of setting of the folded creases. Particular attention is directed to the fact that the roller 44 presses against the web 14 to deflect it inwardly between the rollers 35 and 40 and also that the roller 44 is shorter than the width of the web whereby the outer edge portions commence to curve upwardly ahead of the roller. This operation is clearly shown in Fig. 9.

From the supporting rollers 40, the web passes beneath the next successive folder roller 45 which serves a function similar to the roller 44 as previously described. The roller 45 is shorter than roller 44, however, the length thereof being substantially equal to the spacing between the next outermost scores of the web. The outer edge portions are thereupon given another inward fold which folding is further guided by another deflector element 54 similar to the element 50 as previously described, the slot in the element 54 being shorter, however, than the slot 51 in the element 50 and of a length corresponding substantially to that of the folder roller 45. The web then progresses over the second set of supporting rollers 41 and from whence it passes beneath the third folder roller 46. The outer edge portions of the web, having been folded over twice

5 prior to reaching the roller 46, are sufficiently stiff so that when folded over further during the initial threading operation and drawn over the next set of supporting rollers 42, a further deflector element similar to the elements 50 and 54, as previously described, is unnecessary. In passing from the supporting rollers 42, the web then passes beneath the last folder roller 47 whereupon the opposite edge portions are each given an additional inward fold before passing over the last supporting roller 43. Here again no deflector is required for guiding the folding movement of the outer edge portion, it being merely necessary for the folder roller 47 to press inwardly against the intermediate portion of the web. In this instance the length of the roller 47 corresponds to the spacing between the two innermost scores of the web.

20 In passing over the last supporting roller 43, the web is completely formed into strap; but the strap at this point is relatively stiff because of the multiple layers in each of the folded edge portions. Furthermore, if nothing more were done to the strap, severed short lengths thereof would 25 tend to unfold due to incomplete setting of the paper fibers along the crease lines. As the web is drawn through angles in passing over the supporting rollers 40—43, inclusive, a certain amount of setting of the folds is accomplished so that 30 these rolls may also be aptly referred to as fold setting means interspaced between the folder rolls 44—47. In order to effect further setting of the 35 folds, however, and also to impart a considerable degree of flexibility to the strap, it is then drawn through a plurality of relatively sharp bends in successive opposite directions. In the machine 40 illustrated, a pair of additional rollers 60 and 61 are mounted within turret end plates 62 which are, in turn, secured to the adjacent frame members 24 and 25. As illustrated more clearly in the view of Fig. 1, the strap is trained around the rollers 60 and 61 in opposite directions. By rotatable 45 adjustment of the turret end plates 62, the extent of the bends formed in the paper strap may be varied as may be required to accomplish the desired result. The rollers 60 and 61 may, for convenience, hereinafter be referred to either as fold setting means or strap flexing means or combined fold setting and flexing means.

50 From the roll 61, the strap passes around the puller roller 33 previously described. Idler roller 64 bears against the strap between the roller 61 and the puller roller 33 to insure adequate frictional engagement between the strap and the latter roller.

55 From the description given thus far, it should be apparent why the alternate supporting rollers and folder rollers are arranged in a generally circular configuration. While the folding and fold setting operations could be carried out with a substantially straight line path of travel for the paper web, the operation may be carried out with a considerably shorter total length of travel with the elements arranged in the circular configuration shown. The over-all length of the machine is also reduced to a minimum with the arrangements shown with resultant economy of space requirements. The folding operations face outwardly at each step and which may be clearly viewed by the attendant; and faulty operation, such as of a defective part, may readily be detected. Since all of the working parts are closely adjacent the periphery of the frame, they are readily accessible for such adjustment as may be required. By virtue of the large central open-

ing 26 in the frame members, the web can be easily threaded through the machine for starting or in the event of breakage.

In starting the machine, the end of the paper strap is suitably secured to a spindle 67 rotatably journaled at opposite ends within supporting blocks 68 which are, in turn, slidably mounted upon a pair of spaced apart horizontally extending tracks 69, 70. The spindle 67 is urged toward the puller roller 33 by means of a weight 72 mounted on the end of a pair of chains 73 trained over sprockets 74 and connected to the ends of rods 75 which are secured at their opposite ends to a corresponding one of the blocks 68.

When the end of the strap is secured to the spindle 67 and the latter held in operative engagement with respect to the roller 33 by weight 72, the spindle 67 is rotated at the same peripheral rate of speed as the roller 33. The spindle is, of course, driven in a direction opposite to that of the roller 33 and the strap will be wound up thereupon. As the diameter of the coil of strap on spindle 67 increases, the supporting blocks 68 will be caused to slide outwardly along the supporting tracks 69, 70 but the periphery of the strap coil will always be held against the motor driven roller 33 between the flanges thereof. The flanges provided on roller 33 engaging with the opposite sides of the edges of the coil 16 insure straight winding of the strap upon the coil. Further, longitudinal rollers 78, 79 mounted on the inside of the corresponding supporting tracks 69-70 stabilize the coil 16 during rotation thereof. After the coil or strap has been built up to a reasonable size, the strap may be severed and the end secured and the coil lifted from the blocks 68. The spindle 67 may then be withdrawn, the end of the strap again secured thereto and a new coil wound up thereupon.

Having described the invention in what is considered to be a preferred embodiment thereof, it is desired that it be understood that the specific details are merely illustrative and that the invention may be carried out by other means.

What I claim as my invention is:

1. A machine for forming strap by folding over the opposite edge portions of a relatively narrow web of paper a plurality of times, the folded edge portions meeting substantially along the center line of strap on one side thereof in a nonoverlapping relation, said machine comprising means for forming a plurality of parallel scores longitudinally of the paper web, a plurality of spaced apart supporting rolls mounted in said machine and arranged on the same side of the path of travel of said web, means at the discharge end of said machine for pulling the web therethrough, folding means mounted between each adjacent pair of said supporting rolls and on the opposite side of said web with respect to said supporting rolls, said folding means each comprising a roller bearing against the surface of said web and deflecting it downwardly between each adjacent pair of said supporting rolls, the first of said folding means nearest said scoring means being adapted for folding over the opposite edge portions of said web along the two outermost scores, each of the successive ones of said folding means being adapted for folding over the edge portions along the next adjacent outer scores.

2. A machine for forming strap from a relatively narrow web of paper, said machine comprising a pair of cooperating scoring rolls for forming a plurality of parallel scores longitudinally of the paper web passing therebetween, a plurality of spaced apart supporting rolls mounted in said machine and arranged on the same side of the path of travel of said web, means at the discharge end of said machine for pulling the web therethrough, a folding roll mounted between each adjacent pair of said supporting rolls and on the opposite side of said web with respect to said supporting rolls, said folding rolls being so positioned as to deflect the web downwardly between each adjacent pair of said supporting rolls, the first of said folding rolls nearest said scoring rolls having a length corresponding substantially to the spacing between the two outermost scores along the opposite edges of said web whereby the overhanging opposite edge portions of said web are free to fold upwardly at the opposite ends of said first roll in moving therewith, each of the successive ones of said folding rolls being shorter than the preceding one and of a length corresponding substantially to the spacing between the next two scores on said web, a pair of closely spaced flexing rolls arranged after the last of said folding rolls for causing a pair of relatively sharp reverse bends in the strap passing from said last folding roll.

5. A machine for forming strap by folding over the opposite edge portions of a relatively narrow

plurality of spaced apart fold setting rolls mounted in said machine and arranged on the same side of the path of travel of said web, pulling means at the discharge end of said machine for pulling the web therethrough, folding means mounted between each adjacent pair of said supporting rolls and on the opposite side of the path of travel of said web with respect to said fold setting rolls, said folding means each comprising a roller bearing against the surface of said web and deflecting it downwardly between each adjacent pair of said fold setting rolls, take up means operatively engaged by said pulling means for winding up the strap emerging from said machine.

3. A machine for forming strap from a relatively narrow web of paper, said machine comprising scoring means for forming a plurality of parallel scores longitudinally of the paper web, a plurality of spaced apart rolls mounted in said machine and arranged on the same side of the path of travel of said web, means at the discharge end of said machine for pulling the web therethrough, folding means mounted between each adjacent pair of said rolls and on the opposite side of the path of travel of said web with respect to said rolls, the first of said folding means nearest said scoring means folding said web along the two outermost scores adjacent the opposite edges of said web, each of the successive ones of said folding means folding said web along the next successive outermost scores, said folding means each comprising a roller bearing against the surface of said web and deflecting it downwardly between each adjacent pair of said rolls, said rollers being of progressively decreasing width from said scoring means, and a combined fold setting and strap flexing means arranged after said last folding means.

4. A machine for forming strap by folding over the opposite edge portions of a relatively narrow web of paper a plurality of times, the folded edge portions meeting substantially along the center line of strap on one side thereof in a nonoverlapping relation, said machine comprising a pair of cooperating scoring rolls for forming a plurality of parallel scores longitudinally of the paper web passing therebetween, a plurality of spaced apart supporting rolls mounted in said machine and arranged on the same side of the path of travel of said web, means at the discharge end of said machine for pulling the web therethrough, a folding roll mounted between each adjacent pair of said supporting rolls and on the opposite side of said web with respect to said supporting rolls, said folding rolls being so positioned as to deflect the web downwardly between each adjacent pair of said supporting rolls, the first of said folding rolls nearest said scoring rolls having a length corresponding substantially to the spacing between the two outermost scores along the opposite edges of said web whereby the overhanging opposite edge portions of said web are free to fold upwardly at the opposite ends of said first roll in moving therewith, each of the successive ones of said folding rolls being shorter than the preceding one and of a length corresponding substantially to the spacing between the next two scores on said web, a pair of closely spaced flexing rolls arranged after the last of said folding rolls for causing a pair of relatively sharp reverse bends in the strap passing from said last folding roll.

web of paper a plurality of times, the folded edge portions meeting substantially along the center line of strap on one side thereof in a nonoverlapping relation, said machine comprising a pair of cooperating scoring rolls for forming a plurality of parallel scores longitudinally of the paper web passing therebetween, a plurality of spaced apart supporting rolls mounted in said machine and arranged on the same side of the path of travel of said web, means at the discharge end of said machine for pulling the web therethrough, a press roll mounted between each adjacent pair of said supporting rolls and on the opposite side of the path of travel of said web with respect to said supporting rolls, said press rolls being so positioned as to deflect the web downwardly between each adjacent pair of said supporting rolls, the first of said press rolls nearest said scoring rolls having a length corresponding substantially to the spacing between the two outermost scores formed along the opposite edges of said web whereby the overhanging opposite edge portions of said web are free to fold upwardly at the opposite ends of said first roll in moving therewith, each of the successive ones of said press rolls being shorter than the preceding one and of a length corresponding substantially to the spacing between the succeeding outer two scores formed on said web.

6. A machine for forming strap by folding over the opposite edge portions of a relatively narrow paper web a plurality of times throughout its entire length, the folded edge portions meeting substantially along the center line of the strap on one side thereof in a nonoverlapping relation, said machine comprising a pair of parallel side frame members, a pair of cooperating scoring rolls adjacent the inlet end of said machine for forming a plurality of parallel scores longitudinally of the web passing therebetween, a plurality of spaced apart fold setting rolls rotatably mounted between said frame members in a substantially circular configuration and on the same side of the path of travel of said web through the machine, means at the discharge end of said machine for pulling the web therethrough, a plurality of folder rolls rotatably mounted between said frame members, one of said folder rolls being mounted between each adjacent pair of said spaced apart supporting rolls and on the opposite side of the path of travel of said web with respect to said folder rolls, the first of said folder rolls nearest said scoring rolls folding said web along the two outermost scores adjacent the opposite edges of said web, each of the successive folder rolls folding said web along the next successive pair of scores along the opposite sides of said web, and a combined fold setting and flexing means mounted between said last folder roll and said web pulling means.

7. A machine for forming strap by folding over the opposite edge portions of a relatively narrow paper web a plurality of times throughout its entire length, the folded edge portions meeting substantially along the center line of the strap on one side thereof in a nonoverlapping relation, said machine comprising a pair of parallel frame members, a pair of cooperating scoring rolls adjacent the inlet end of said machine for forming a plurality of parallel scores longitudinally of the web passing therebetween, a plurality of spaced apart supporting rolls rotatably mounted between said frame members in a substantially circular configuration and on the same side of the path of travel of said web through the machine, means at the discharge end of said machine for pulling

60
65
70

the web therethrough, a plurality of folder rolls rotatably mounted between said frame members, one of said folder rolls being mounted between each adjacent pair of said spaced apart supporting rolls and on the opposite side of the path of travel of said web with respect to said supporting rolls, said folder rolls being so positioned as to press the web downwardly between each adjacent pair of said supporting rolls, the first of said folder rolls nearest said scoring rolls having a length corresponding substantially to the spacing between the two outermost scores along the opposite edges of said web whereby the overhanging opposite edge portions of said web are free to fold upwardly at the opposite ends of said first folder roll in moving therewith, each of the successive folder rolls being shorter than the preceding one and having a length corresponding substantially to the next successive pair of scores along the opposite sides of said web.

8. A machine for forming strap by folding over the opposite edge portion of a relatively narrow paper web a plurality of times throughout its entire length, the folded edge portions meeting substantially along the center line of the strap on one side thereof in a nonoverlapping relation, said machine comprising a pair of parallel frame members, a pair of cooperating scoring rolls adjacent the inlet end of said machine for forming a plurality of parallel scores longitudinally of the web passing therebetween, a plurality of spaced apart supporting rolls rotatably mounted between said frame members in a substantially circular configuration and on the same side of the path of travel of said web through the machine, means at the discharge end of said machine for pulling the web therethrough, a plurality of folder rolls rotatably mounted between said frame members, one of said folder rolls being mounted between each adjacent pair of said spaced apart supporting rolls and on the opposite side of the path of travel of said web with respect to said supporting rolls, said folder rolls being so positioned as to press the web downwardly between each adjacent pair of said supporting rolls, the first of said folder rolls nearest said scoring rolls having a length corresponding substantially to the spacing between the two outermost scores along the opposite edges of said web whereby the overhanging opposite edge portions of said web are free to fold upwardly at the opposite ends of said first folder roll in moving therewith, each of the successive folder rolls being shorter than the preceding one and having a length corresponding substantially to the next successive pair of scores along the opposite sides of said web, and a pair of closely spaced rolls arranged after the last of said folder rolls for forming a pair of relatively sharp reverse bends in said folded web.

9. A machine for forming strap from a paper web, said machine comprising a pair of parallel frame members, a scoring means adjacent the inlet end of said machine for forming a plurality of parallel scores longitudinally of the web, a plurality of spaced apart fold setting rolls rotatably mounted between said frame members in a substantially circular configuration and on the same side of the path of travel of said web through the machine, means at the discharge end of said machine for pulling the web therethrough, a plurality of folding means mounted between said frame members, one of said folding means being mounted between each adjacent pair of said spaced apart fold setting rolls and on the opposite side of the path of travel

of said web with respect to said fold setting rolls, the successive ones of said folding means being adapted to fold over the outer edge portions of said web along corresponding successive scores from the opposite outer edges thereof inwardly toward the center.

10. A machine for forming strap from a relatively narrow paper web, said machine comprising a pair of parallel frame members, a plurality of spaced apart fold setting rolls rotatably mounted between said frame members in a substantially circular configuration and on the same side of the path of travel of said web through the machine, a puller roll at the discharge end of said machine for pulling the web therethrough, a plurality of folding means mounted between said frame members, one of said folding means being mounted between each adjacent pair of said spaced apart fold setting rolls and on the opposite side of the path of travel of said web with respect to said fold setting rolls, a spindle for receiving folded strap from said machine, means supporting said spindle and holding the coil thereon in engagement with said puller roll.

11. A machine for forming strap from a relatively narrow paper web, said machine comprising a pair of parallel side frame members, a plurality of spaced apart fold setting rolls rotatably mounted between said frame members, and on the same side of the path of travel of said web through the machine, a puller roll at the discharge end of said machine for pulling the web

therethrough, a plurality of folding means mounted between said frame members, one of said folding means being mounted between each adjacent pair of said spaced apart fold setting rolls and on the opposite side of the path of travel of said web with respect to said fold setting rolls, a spindle for receiving folded strap from said machine, a horizontal track having one end adjacent said puller roll, means slidably supporting said spindle on said track for movement toward and away from said puller roll, and means urging said spindle toward said puller roll.
